EDGE TRIMMING MEANS FOR USE IN
ROTARY PRINTING PRESSES

William Andrew Pratt, Watford, England

Application February 28, 1942, Serial No. 432,858
In Great Britain May 29, 1941

10 Claims. (Cl. 164—67)

This invention relates to edge trimming mechanism for use with particular advantage in rotary printing presses. As is well known the sheets or what are usually known as copies on their exit from the printing press are severed from the web by mere slitters or perforators with the result that their edges are rough or serrated and in order that such copies should have smooth or clean cut edges they have to be trimmed after leaving the press in a separate trimming machine.

The object of this invention is to dispense with this separate trimming operation and to provide means enabling such sheets or copies to be provided with clean cut edges before they leave the printing press so that the work would come straight from the printing press complete and ready for dispatch. The time therefore hitherto taken in handling the work from the presses by various means of transportation to the trimming machines and after trimming again transporting it to packing benches will be eliminated and the number of men required therefor will thereby be dispensed with.

With this object in view according to this invention improved edge trimming mechanism is actually embodied in the printing press itself, i. e., preferably in what is known as the folding section of the press and comprises cutting means for trimming the head and tail edges of the printed matter and cutting means for trimming the fore edge thereof in such co-operative association as to effect these trimming operations automatically in a continuous performance within the press as will hereinafter be more fully described by reference to a constructional form of the invention found to fully afford the advantages above referred to and illustrated by way of example in the accompanying drawings in which:

Fig. 1 is a side elevation of what is known as the folding section of a rotary printing press embodying the trimming mechanism according to this invention;

Fig. 2 is a plan view thereof;

Fig. 3A is a detail face view of the means for the accommodation of the straight knife for use on a rotary member hereinafter referred to as the cutting cylinder;

Fig. 3B is a side elevation thereof;

Fig. 4A represents detail plan of a useful form of this knife;

Fig. 4B is an enlarged end view showing the edge portion thereof, and

Figs. 5A and 5B show respectively a face and

edge view of the anvil employed in the folding cylinder for co-operation with said knife in the cutting cylinder aforesaid.

According to this invention the trimming mechanism consists of cutters or knives adapted to cut the head and tail edges of a copy or sheet when the folder is running as a tabloid production or the fore edge thereof when the folder is running to a full page newspaper production and a cutter for trimming the fore edge of the copy when running as a tabloid or respectively the heads and tails when running as a full newspaper production all of which are arranged preferably as shown within the folding section of the press.

As shown the cutters 2 for trimming the head and tail edges of a copy when the folder is running as a tabloid production or the fore edge when the folder is running to a full page newspaper production are arranged respectively on a driving shaft 1 and a driven shaft 1A which are journaled parallel one with the other in bearings 1 and 1A mounted upon or forming part of the stationary side frames 1C of the press. These cutters 2 consist of co-operating pairs of rotary shearing knives which are secured in their proper relation at the respective ends of the two shafts 1 and 1A being preferably mounted on or forming part of collars 2A which are adjustable on these shafts so as to enable the circular knives 2 to be set for their accurate relationship with the requisite precision and according to the width of the copy. The driven shaft 1A is adjustable in relation to the shaft 1 by the bearings 1A being pivoted at 1B and equipped with tensioning devices adapted to bear on swivels 8 which are mounted in lugs 8A projecting from the said bearings 1A. Each tensioning device as shown comprises a tensioning screw 9 which is screwed into a bracket 11 mounted on the adjacent side frame 1C and is fitted with a spring 10 confined between the swivel 8 and a collar 9A on the screw 9. As shown in Fig. 2 felt or rubber pads 3 are fitted to the shaft 1A bearing against the inner sides or faces of the knives 2 on that shaft and adapted to support respectively the head and tail or the fore edge of a copy while the latter is being trimmed. In order to support and prevent any creasing of the copy or sheet during the trimming operation cylindrical covers or sections 4 are provided to bridge the gap between the collars carrying the circular shearing knives 2. Laterally of and in juxtaposition with the outer faces of the knives 2 on shaft 1 are adjustable guide shoes 12 for guiding the trim-

mings to a chute shown at 16. Each of these guide shoes 12 shaped preferably as shown in Fig. 1 is associated with or forms part of an adjustable slide 13 mounted in a stationary guide member 13A enabling by displacement in its longitudinal sense the respective guide shoe 12 to be adjusted to the correct position in relation to the cutters and to the chute 16. The slides 13 are as shown connected by a common cross-bar or rod 13B adapted to be actuated by a manually operable lever 14 which is hinged in a bracket 14A secured to a stationary frame member 14B thus enabling the slides 13 and thereby both guide shoes 12 jointly to be appropriately set. These guide shoes 12, moreover, are adapted to be used for breaking the trimmed strips by co-operation of their knife edged ends with the front edge of the chute 16 when they are closed, i. e., have been set from their outer or inoperative to their inner or operative position. Each guide shoe is also provided with a blade like member 15 the curved face of which clearly shown in Fig. 1 serves for separating the trimmings from the copy or sheet immediately after they are severed by the cutters 2. The chute 16 having the form of a shallow pan or trough with its receiving or inner edge extending close to the curved ends of the guide shoes 12 is with advantage mounted on rocker arms 16A and terminates in a waste pipe 17 which is attached to a suction or exhaust fan (not shown) to take away the waste trimmings.

Associated with the cutter device 2 above described is the cutting device 18, 20 for use in trimming the fore edge of the copy when the folder is running as a tabloid or respectively the heads and tails when running as a full newspaper production. This device is with advantage embodied in the cutting cylinder 19 which is in direct co-operation with the folding cylinder proper 21. Each such device comprises a plain edged knife 18 preferably of the type shown in Fig. 4A made of special steel which is ground to suitable cutting angles as shown in Fig. 4B proved by experiment to give clearance as the knife cuts the signature or copy which latter may consist of any number of sheets.

The knife 18 is with advantage adjustably mounted in a knife case 18A as shown in Fig. 3 which is embedded in a longitudinal recess 19A provided in the cutting cylinder 19. In the example here illustrated the knife is fitted between two jaws or bolsters 18B which are lodged within a recess 18C within its holder or knife case 18A proper, compression springs 18D being employed on which the bolsters 18B are yieldingly supported. Between the bolsters 18B the position of the knife 18 and of its projecting edge can be accurately set by the usual means of any appropriate type such as for example as indicated in Figs. 3A and 3B by a fine adjustment of the lateral clamping screws 18E adapted to pass through the body of the case 18A and notches 18F in the shank edge of the knife in conjunction with cross pins 18H inserted through the slots 18I in the body of the knife. The number of cutting knives so arranged in the cutting cylinder will obviously depend upon the layout of the job or folder. The knife 18 during its rotation with the cutting cylinder 19 is adapted to effect the cutting in co-operation with an anvil 20 embedded in the folding cylinder 21. The number of anvils is dependent on the layout of the job or folder and there may be two anvils

to one knife or one to each or a multiple thereof. Each anvil is shaped like a bar or strip as shown in the views in Figs. 5A and 5B and is fitted at the requisite height within a corresponding recess in the folding cylinder in the cutting line of the corresponding cutting knife. These anvils are preferably made of steel, hardened and ground parallel to make it possible for the finest adjustment of the corresponding knife to make a clean cut of the edge. Phosphor bronze or any other unyielding material may, however, also be used for making these anvils. It is of importance that this embodiment of a cutting knife and of its corresponding anvil in their respective cylinders is such that when the copy or sheet arrives at the contact or co-operating point of the knife and its anvil it is cleanly severed by a wiping or kiss contact of the knife with the anvil. The cutting cylinder 19 and the folding cylinder 21 are arranged to rotate together so that whatever the ratio may be between the two cylinders the knife and cutting anvil are timed to make kiss contact in exactly the same position each time they meet.

The shafts 1 and 1A of the cutting device provided with the rotary shearing knives 2 are shown to be driven by a gear unit 5 and 6 which in the instance shown derives its driving movement through the gear 24 associated with the stitching cylinders 22, 23 of the press.

In operation which can be readily followed from the illustration in Fig. 1 the printed matter or copy 28 after leaving the stitching cylinders 22, 23 is caused to pass through the cutter set 2 in which the heads and tails of the copy when the folder is running as a tabloid or the fore edge when the folder is running as a newspaper production are trimmed as it passes through the folder during which operation the trimmings are immediately broken and deflected by the shoes 12 into the chute 16 whence they are removed as stated preferably by the action of a suitable exhaust or suction fan. With the head and tail edges of the tabloid or the fore edge of a newspaper thus in a clean and smooth condition the copy with its fore edge or a newspaper with its tail edge then travels into the cutting device 18, 20 being preferably supported and guided by a pair of drawing rollers 25, 26 driven by an idler 27 from the driving shaft 1. After the respective edge has been trimmed by the contact between the edge of the knife 18 and its anvil 20 it is caused to travel on to the delivery ready for stacking and dispatch. Practical experience has shown that the cutting edge of the knife gives most satisfactory results if the intersecting surfaces producing the cutting edge form an angle with one another of 45° as shown in Fig. 4B when it was found that a true wiping or kiss contact with the corresponding anvil 20 will be obtained.

Experience has also shown that by arranging and constructing the trimming mechanism in the manner above described the invention will do away with a considerable amount of labour, saving many hours thus gained which will allow of the press times being put back and dispensing also with the need for large numbers of automatic trimming machines with consequent economy of floor space thus being of great advantage to printing concerns. This applies equally to printing concerns accustomed already to trim their publications and also to printers who for reasons of cost and time do not. For the latter it

will definitely improve the appearance of the periodical, newspaper or publication which in turn would increase their sales value.

I claim:

1. In a rotary printing press having a folding section the provision in combination with the folding section of edge trimming mechanism comprising cutting means for trimming the heads and tails of a copy as well as means for trimming the fore edge thereof both said means being arranged in cooperative association for effecting the cutting of the head and tail edges as well as of the fore edge of said copy in a continuous automatic operation within the press.

2. In a rotary printing press having a folding section, the provision in combination with the folding section of edge trimming mechanism arranged within said folding section and adapted to trim the head and tail edges of a copy when the folder is running to a tabloid production and trimming mechanism arranged likewise within said folding section and adapted to trim the fore edge of the copy when the folder is running to a full newspaper production.

3. In a rotary printing press having a folding section the provision in combination with the folding section of edge trimming mechanism comprising a trimming device arranged within said folding section and adapted to trim the fore edge of the copy when the folder is running to a tabloid production and a trimming device arranged likewise within said folding section and adapted to trim the heads and tails of the copy when the folder is running to a full newspaper production.

4. In a rotary printing press having a folding section the provision in combination with the folding section of trimming mechanism arranged within said folding section and consisting of rotary circular knives adapted to cut the head and tail edges of a copy when the folder is running as a tabloid production and a rotary straight edged cutter for trimming the fore edge of said copy when running as a full newspaper production.

5. In a rotary printing press having a folding section the provision in combination with the folding section of mechanism within said folding section for trimming the head and tail edges as well as the fore edge of a copy consisting of rotary circular shearing knives adapted to cut the fore edge of said copy when the folder is running to a tabloid production and a straight edged rotary cutter for trimming the head and tails of said copy when the folder is running as a full page newspaper production.

6. In a rotary printing press having a folding section the provision in combination with the folding section of mechanism arranged within said folding section for trimming the head and tail edges as well as the fore edge of a copy comprising rotary circular shearing knives arranged in juxtaposition to cooperate in pairs respectively in an adjustable manner, pads provided for supporting the edges of said copy and covers between said knives for preventing creasing of the printed matter during the trimming operation.

5 7. In a rotary printing press having a folding section the provision in combination with the folding section of mechanism for trimming the head and tail edges as well as the fore edge of a copy comprising in combination with rotary circular shearing knives adjustable guide shoes adapted to divert the trimmings and with a chute for their removal associated with said guide shoes for causing said trimmings to be broken and directed into said chute.

15 8. In a rotary printing press having a folding section the provision in combination with the folding section of mechanism for trimming the head and tail edges as well as the fore edge of a copy comprising in combination with rotary circular trimming knives adjustable guide shoes adapted to divert the trimmings and a chute for receiving said trimmings, and means in communication with said chute for removing said trimmings from said chute by exhaustion.

25 9. In a rotary printing press having a folding section the provision in combination with the folding section of mechanism for trimming the head and tail edges as well as the fore edge of a copy comprising rotary circular trimming knives arranged in juxtaposition to cooperate in pairs respectively in an adjustable manner, guide shoes for diverting the trimmings, and manually operable slides connected to said guide shoes for adjusting the same.

35 10. In a rotary printing press having a folding section the provision within the folding section of mechanism for trimming the head and tail edges as well as the fore edge of a copy comprising in combination with rotary shearing trimmers a cutting device constituted by a straight edged knife adjustably fitted in a rotatable cylindrical carrier and a corresponding anvil carried by an 45 associated cylinder adapted in cooperation with said carrier during rotation to effect a clean cut by mere wiping contact.

WILLIAM ANDREW PRATT.
